UNITED STATES PATENT OFFICE.

PAUL R. WERNER, OF PHILADELPHIA, PENNSYLVANIA.

COLLAR-BUTTON.

1,296,888.

Specification of Letters Patent. Patented Mar. 11, 1919.

Application filed July 10, 1918. Serial No. 108,416.

To all whom it may concern:

Be it known that I, PAUL R. WERNER, a citizen of the United States, residing in Philadelphia, Pennsylvania, have invented 5 Collar-Buttons, of which the following is a specification.

One object of my invention is to provide a form of button particularly designed for holding a collar at its middle portion to the 10 neck band of a shirt, the button being of a construction which, while permitting of the collar being easily mounted upon it, shall effectually hold said collar from accidental detachment, particularly during the connecting of its ends to a second button on the 15 front of the shirt.

This object and other advantageous ends I secure as hereinafter set forth, reference being had to the accompanying drawings, in 20 which:

Figure 1 is a perspective view of a collar button constructed according to my invention;

Figs. 2 and 3 are respectively a front elevation and a plan of the collar button shown in Fig. 1;

Fig. 4 is an inverted plan of my collar button showing in dotted lines the relative position of the part of the collar which it is 30 intended to hold in place; and

Fig. 5 is a central vertical section of my collar button, showing its position relatively to the other parts with which it is associated in use.

In the above drawings 1 represents the body of the button which is preferably in the form of an elongated metal plate or piece of sheet metal characterized by having two substantially semi-circular abutments 2 35 projecting from one of its elongated edges respectively adjacent the ends thereof and also by a tongue 3 which is bent back at right angles to the general plane of said body from that portion of the edge thereof 40 lying between said abutments 2. After extending back for a distance which in the case illustrated is substantially equal to one-half the width of the body, said tongue is 45 bent down and curved inwardly until its extremity passes through and lies slightly 50 beyond the plane of the central part of said body; it being noted that the latter is preferably given a slight circular curvature so 55 that it may substantially conform to the curvature of the neck of the wearer and hence to that of the collar. As shown in Fig. 2

said tongue preferably narrows as it extends downwardly and its extremity has a circularly curved outline.

Under conditions of use the collar button 60 is placed in the space or pocket between the body of the neck band 4 and a flap 5 in which is formed a button hole for the reception of said button, and its tongue 3 is passed outwardly through this hole. The 65 body 1 then conforms to or lies parallel with the band 4 which has a curved form determined by the neck of the wearer, and when in this position the button cannot fall out of place or become dislodged by reason of the 70 part 8 which extends through the button hole at right angles to the adjacent portions of the band and because of the action of the abutments 2 and tongue 3 which coact to prevent said button moving out of this 75 position.

In placing a collar on the button, the tongue passes through the button hole with the collar in a position practically at right angles to that finally assumed, and as it is 80 moved upwardly on said tongue it is gradually swung toward its final position although said movement is opposed by the abutments 2. As the upward movement of the collar is continued, it is slightly bent by 85 the abutments until just as the neck 8 of the tongue enters the button hole, the springiness of the collar by reason of the combined action of the tongue and abutments, causes it to snap into its final vertical 90 position in which said neck 8 extends through the button hole at right angles to the adjacent portions of the collar. When in this position, the tongue bends inwardly 95 the part of the collar band under the button hole since its lower extremity lies in or slightly beyond a plane surface substantially parallel with or including the abutments.

Thereafter owing to the action of the abutments 2, the button tends to remain in 100 the position shown in Fig. 5 since before it can be tilted sufficiently to withdraw the tongue or permit the collar to slip down over the same, said lugs must press in and to some extent bend the collar structure in 105 order to permit it passing from the part 8 of the tongue around the corner 7 thereof onto its narrow portion.

Owing to this combined action of the abutments and the lower end of the tongue 110 therefore, the collar cannot slip downwardly off of the button during the further opera-

tion of attaching its front ends to the button at the front of the shirt; and it is noted that owing to the rearward projection 8 or neck of the tongue, the outside flap 9 of the collar is held away from the inside flap 6, leaving a space in which a necktie may be easily inserted and thereafter adjusted.

It is especially to be noted that the sharp inward bend between the body of the button and its portion 8, as well as the relatively sharp angular corner 7 of the tongue and the termination of the latter relatively to the abutments 2, are essential features of my invention, since if said abutments were omitted and the angularly bent tongue alone employed, the collar button could easily tilt into an inclined position in which the collar could move off of said tongue with the greatest ease. Likewise the mere use of the

abutments 2 without the sharp angularly bent tongue would likewise fail to accomplish the purposes I desire, since there would be no obstacle to the sliding of the collar downwardly on said tongue even though it did not tilt.

25

I claim:—

A collar button consisting of a body having two extensions forming abutments projecting from one edge; and a tongue projecting from the same edge and between said abutments, said tongue being bent sharply adjacent the body to lie in a plane at right angles thereto and being thereafter again bent at right angles and curved inwardly into and terminating in the plane of the abutments.
